UNITED STATES PATENT OFFICE.

ALBERT EDWARD SEATON, OF HULL, ENGLAND.

HYDRAULIC JACK.

SPECIFICATION forming part of Letters Patent No. 511,096, dated December 19, 1893.

Application filed February 3, 1893. Serial No. 480,916. (No model.)

To all whom it may concern:

Be it known that I, ALBERT EDWARD SEATON, a subject of the Queen of Great Britain, residing at Hull, in the county of York, England, have invented certain new and useful Improvements in Hydraulic Jacks, applicable to forcing the coupling-bolts out of marine-engine, propeller, and other shafting, and the like purposes, of which the following is a specification.

My invention relates to improvements in hydraulic jacks which are applicable to forcing the coupling bolts out of marine engine, propeller and other shafting and the like purposes and the objects of my improvements are to provide an effective portable appliance for forcing the bolts out of the couplings of marine engine, propeller or other shafting, or for other similar purposes, thereby avoiding the delay, expense and injury to the couplings and bolts which are sometimes caused by the means ordinarily employed. I attain these objects in the manner illustrated in the accompanying two sheets of drawings, in which—

Figure 1. represents a bolt forcing jack (partly in section) placed in position for forcing a bolt out of a shaft coupling. Fig. 2. is a section through the frame of the jack looking toward the claw end of the same. Figs. 3 and 4. represent an additional appliance to facilitate the use of a hammer when it is desired to give an impact to the ram when the hydraulic pressure is full on. Fig. 5. represents the bolt forcing jack converted into a lifting jack by means of a specially adapted appliance or appliances. Fig. 6. is a section through the frame of the jack so converted looking toward the claw end of the same. Figs. 7., 8. and 9. represent the specially adapted appliance or appliances hereinbefore referred to for converting the bolt forcing jack into a lifting jack.

Similar letters refer to similar parts throughout the several views.

I construct my improved forcing jack in form somewhat resembling a hydraulic punch bear or riveter, the head being fitted with hydraulic ram, power pump, valves and other necessary appliances and fittings, similar to those usually employed in hydraulic jacks,

punching bears, and the like hydraulic implements, and so far as this part of my improved appliance is concerned, I lay no claim as to novelty.

55

a, is the frame of my improved jack, *b*, the head end of the same which contains the ram, *c*, and forms one end of what may be called the jaw, and corresponds to the punch or ram end of a hydraulic punch bear or riveter. The other end of the jaw, *d*, which corresponds to the die end of a punching bear or riveter, and which for convenience I will call the claw end, is made with a semicircular opening large enough to allow of the head of a bolt to clear when being forced out of the coupling, sufficient surface being provided round the opening of this end of the jack to give a good hold or bearing on both sides of the head of the bolt during the operation.

70

e, represents a shaft coupling in section.

f, represents a coupling bolt.

The jaw of my improved jack, from the head or ram end *b*, to the claw end, *d*, is made long enough and deep enough to span both flanges of the coupling, *e*, and the nut end of the bolt, *f*, when in position, so that the center of the ram, *c*, and the center of the space at the claw end may be in line with the center of the bolt; thus when the jack is properly adjusted into position and pressure is applied to the ram by means of the pump, the end of the ram which is suitably formed for the purpose is forced against the end of the bolt, which as the pressure increases is forced out of the coupling; the resistance to the ram being received by the claw end of the jack which as before stated is fixed at the opposite side of the coupling.

75

The stirrup formed appliance *g*, illustrated in Figs. 3 and 4, Sheet 1, is to facilitate the use of a hammer when it is desired to give an impact to the ram when the hydraulic pressure is full on, *h*, being the point at which the blow would be given and, *i*, the button formed head which may be part of the stirrup formed appliance, or part of the ram or in some cases preferably apart from and independent of the same.

80

The body or frame of my improved jack with the ram, cylinder and pump case, I construct in one or more parts either in steel or

90

95

100

other suitable metal, the form of the frame being so designed as to combine lightness with strength.

For the convenience of moving the jack about and fixing it into position, a loop or shackle may be so placed in the frame that when the jack is suspended, it will hang horizontally or in any other position which may be found convenient. *j*, is a hole in the frame of the jack for such lifting shackle or loop.

Although the jack herein described is more particularly designed for forcing bolts, its usefulness is by no means restricted to such purpose as by using a specially adapted appliance in the form of a bolt, *k*, so as to extend the action of the ram beyond the claw end of the jack it can be at once used as a lifting jack.

l, is a bush or liner provided with ribs or projections, *n*, *n*, corresponding to recesses, *o*, *o*, provided in the claw end of the jack by means of which bush the bolt, *k*, may be guided in the claw end of the jack, *m*, being a pin or set screw by means of which the bush, *l*, is kept in position. In some cases for the greater convenience of such a combination of uses, a specially adapted appliance or appliances can be supplied with the jack, by means of which my improved forcing jack can be readily converted into a lifting jack.

As a further modification, in lieu of the specially adapted appliance herein described as a bush or liner and illustrated in Figs. 8 and 9, the specially adapted appliance, *k*, in

the form of a bolt illustrated in Fig. 7, may, 35 as shown by the dotted lines, have the stalk or shank increased in size at its lower end to fit the opening in the claw end of the jack and is retained in position by the ribs, *n*, *n*, formed on both sides of the bolt, *k*, corresponding to the groove or grooves, *o*, *o*, in the claw end of the jack so that when the bolt, *k*, is inserted endwise into the claw end of the jack it can only slip out in one direction, viz., that in which it is inserted. 40

Having fully described my invention, what I desire to claim and secure by Letters Patent is—

1. In a hydraulic jack the combination with a yoke of a ram placed in one end thereof, 50 grooved claws formed on the other end a hollow guide piece engaging the grooves of said claws and a bolt *k* actuated by said ram and guided by said guide piece substantially as set forth.

2. In a hydraulic jack the combination with a yoke of a ram placed in one end thereof, grooved claws formed on the other end, a hollow guide piece adapted to be set into said grooves at will, a bolt actuated by said ram and guided by said guide piece and a stirrup arranged to be struck by a hammer said stirrup being mounted on said yoke for starting said ram substantially as set forth. 60

ALBERT EDWARD SEATON.
